H. ROSSET

Des. 163,967

COVER FOR PAINT CANS

Filed May 4, 1950

FIG. 1.

FIG. 2.

FIG. 3.

Inventor:
Harry Rosset,
By Schrader, Merriam,
Hoffman, Brady, Atty.

UNITED STATES PATENT OFFICE

163,967

COVER FOR PAINT CANS

Harry Rosset, Chicago, Ill., assignor to Harbil
Manufacturing Co., Inc., a corporation of Illinois

Application May 4, 1950, Serial No. 9,697

Term of patent 14 years

(Cl. D58—26)

To all whom it may concern:

Be it known that I, Harry Rosset, a citizen of the United States, residing at Chicago, in the county of Cook and State of Illinois, have invented a new, original, and ornamental Design for a Cover for Paint Cans, of which the following is a specification, forming a part hereof.

Figure 1 is a top plan view of a cover for paint cans, embodying my new design;

Figure 3 is a bottom plan view thereof.

I claim:

The ornamental design for a cover for paint cans, as shown.

HARRY ROSSET.
